UNITED STATES PATENT OFFICE.

PAUL GABRIEL TRIQUET, OF PARIS, FRANCE.

APPARATUS FOR STERILIZING LIQUIDS BY MEANS OF ULTRA-VIOLET RAYS.

1,030,692.

Specification of Letters Patent. Patented June 25, 1912.

Application filed April 19, 1911. Serial No. 622,116.

To all whom it may concern:

Be it known that I, PAUL GABRIEL TRIQUET, a citizen of the French Republic, and resident of Paris, France, have invented 5 certain new and useful Improvements in Apparatuses for Sterilizing Liquids by Means of Ultra-Violet Rays, of which the following is a specification.

This invention relates to an apparatus for 10 sterilizing liquids and more especially water, by means of the action of the ultra-violet rays.

The accompanying drawings: Figure 1 is a plan view partly in section, of my improved apparatus. Fig. 2 is an enlarged detail top plan view of the apparatus, parts being shown in horizontal section. Fig. 3 is a cross section on line D—D of Fig. 2. Fig. 4 is a side elevation of the main body 20 portion of the apparatus not yet been inserted in the apparatus.

The numeral 105 indicates a main body portion or receptacle having end flanges 105^x and side flanges 123. Connected to the 25 end flanges 105^x are tapered inlet and outlet flues 150, the outer ends of which are annular as at 151 to form journals. On one side of the main body portion 105 is secured a casing or cover 152 provided with flanges 30 122 and a plurality of partitions 120, the latter extending inwardly and terminating in a plane with the surface of the side wall of the receptacle. The partitions 120 form a plurality of pockets 117 to receive lamp 35 attaching means. In each pocket are lugs 121 to form guides for stirrups in which the lamps are secured. The opposite side wall of the main body portion or receptacle is formed with a plurality of openings 106, 40 there being an opening opposite each pocket 117. Fitting over each opening is a cover 109, formed with a pocket 109^x to receive the end of a lamp. There is a stirrup for each lamp 107 and it extends across the receptacle 105 and into the pockets 117 and 109^x. Each stirrup is provided with upturned ends which carry devices which engage the opposite end of a lamp, to support the latter in operative position.

50 Each mercury vapor lamp 107 comprises a tube or quartz or other vitrified material which is pervious to ultra-violet rays and from each end of the lamp leads a wire 112, connected to binding posts 114 and 116.

55 In order that access may be had with the interior of the receptacle 105 for the inser-

tion or withdrawal of the lamps, I provide special means for fastening the covers 109 in position. Coöoperating with each cover 109 is a yoke 110 having its ends 111 bent 60 inwardly toward each other to embrace the upper and lower side flanges 123. The yoke is formed with a threaded opening to receive a set screw 117, the inner end of which engages the end of the cover so as to bind 65 it tight against the receptacle.

The annular ends of the inlet and outlet flues fit in the inlet and outlet pipes 155 and 156 respectively. Fitting in each of the inlet and outlet pipes adjacent the journals 70 on the receptacle are packing glands 157 to form tight joints to prevent leakage.

In operation the parts are assembled as shown in Fig. 1 and the water is passed through the apparatus. The receptacle 105 75 is turned so as to incline the lamps which is quite essential. As the water passes through the apparatus the rays of light have a sterilizing effect and the water is purified.

To remove a lamp one of the set screws 117^x is released and the coöoperating yoke 110 is moved to one side and the cover 109 can be removed and the lamp withdrawn.

Having now fully described my said invention, what I claim and desire to secure by Letters Patent, is:

1. An apparatus for sterilizing water comprising in combination with the water duct, a receptacle, means for inserting said receptacle in said water duct so as to allow its being rotated and to cause the water to pass through it, the said receptacle comprising a body, a plurality of openings provided in one of the side walls of said body, a cover having as many sockets as there are openings in said body, means for tightly securing the said cover to the side of the body opposite of said openings so as to cause the said sockets to face the said openings, a cap 90 for each opening, means for tightly applying said cap to its opening, a mercury vapor lamp for each pair of openings and sockets, and means for supporting said lamps, these means comprising a stirrup having a hollow body and means for adjustably holding the lamps between the branches of said stirrup and conductors for conveying current to said lamp, one of said conductors passing through said hollow body of the stirrup, means for securing said stirrup at one end 100 to the inside of said cap, and means for 105 110

holding the opposite end of said stirrup in the corresponding socket, substantially as and for the purpose set forth.

2. An apparatus for sterilizing water by 5 ultra-violet rays comprising a receptacle having reduced ends and formed with inlet and outlet openings, the portion of the receptacle between the reduced ends having sockets on one side and openings on the opposite side in alinement with said sockets, mercury vapor lamps mounted in said sockets and openings, covers for the openings, and means for securing the covers.

3. An apparatus for sterilizing water by 15 ultra-violet rays comprising a receptacle formed with a plurality of oppositely disposed sockets, mercury vapor lamps having their ends mounted within the sockets, means for supporting the mercury vapor 20 lamps, and detachable means for gaining access to the sockets for insertion, or withdrawal of the lamps.

4. In an apparatus of the class described, the combination of a receptacle formed with 25 sockets, mercury vapor lamps detachably mounted in the sockets, detachable means on the receptacle for covering or uncovering the sockets to insert or withdraw the

lamps, yokes in the receptacle and extending in the sockets to support the lamps, 30 means in the sockets for holding the yokes in position in the receptacle, inlet and outlet flues secured to the ends of the receptacle and means for revolubly mounting the inlet and outlet flues whereby to permit of the 35 turning of the receptacle.

5. In an apparatus of the class described, the combination of a receptacle formed with sockets, mercury vapor lamps detachably mounted in the sockets, detachable means on 40 the receptacle for covering or uncovering the sockets to insert or withdraw the lamps, inlet and outlet flues at the ends of the receptacle, an inlet pipe communicating with the inlet flue, an outlet pipe communicating 45 with the outlet flue and means for revolubly mounting the inlet and outlet flues on the inlet and outlet pipes, whereby to permit the receptacle being turned.

In testimony whereof I have hereunto set 50 my hand in presence of two witnesses.

PAUL GABRIEL TRIQUET.
